BOTTOM HOLE CHOKE

Frank F. Bridwell, Alice, Tex., and George W. Morrison, deceased, late of Alice, Tex., by Clara Pauline Morrison, executrix, Alice, Tex.

Application July 10, 1944, Serial No. 544,202

7 Claims. (Cl. 166—2)

1

This invention relates in general to bottom hole chokes and more particularly has reference to a wire line bottom hole choke assembly capable of being run in and withdrawn through tubing having restrictions above the choke receiving portion thereof.

Wire line bottom hole chokes which may be run in the tubing, latched in place and withdrawn therefrom as constructed heretofore have consisted of a hollow body of tubular formation. For the purpose of holding such a body down, it has been customary in the past to employ slips which are wedge-shaped members with upwardly directed teeth on their outer surfaces and so arranged that when they are moved downwardly with respect to the body on which they are mounted they will also move outwardly so as to grip the inner wall of the tubing and prevent upward movement of the body.

Quite often it is desirable to have restrictions in the tubing necessary for certain types of gas lift equipment and it would be desirable to have a choke assembly of such size as to pass by said restrictions. It was impossible to construct the previously used types of bottom hole choke in such manner as to accomplish this result because slips have a limited amount of possible expansion. Theoretically the expansion of slips is limited to their thickness at their thicker ends but actually the expansion of slips is in practice limited to approximately half of their maximum thickness. Obviously the thicker the slips are made the thicker it will be necessary to make the mandrel or body on which they are mounted, and if this mandrel or body is to have a passageway through the central portion thereof, the strength of materials available and the sizes of the flow openings required becomes such that the making of a structure small enough in diameter to pass through substantial strictures in the tubing becomes an impossibility.

The principal object of this invention is to provide a bottom hole choke structure which may be substantially smaller in overall size than the tubing in which it is to be used so that it may pass restrictions in the tubing such as restrictions occasioned by the employment of certain types of gas lift apparatus.

Another object of this invention is to provide a bottom hole choke structure having a latching assembly and means for suspending a choke from the latch assembly for communication with the space within the well tubing about the latch assembly.

Still another object of this invention is to pro-

2

vide a bottom hole choke structure having a latching assembly of overall dimensions smaller than those of the tubing including all restrictions in the tubing, means for suspending a choke from the latch assembly for communication with the space within the well tubing about the latch assembly, and means for positioning and anchoring the latching assembly within the tubing without restricting the flow from the space within said tubing about said latching assembly up through the tubing.

With these and other objects in view as will appear more fully hereinafter the present invention resides in the parts and combinations shown in the drawing and set forth in the following description.

In the drawing:

Figure 1 is an axial sectional view of the lower portion of well tubing having a bottom hole choke according to the present invention located therein in unlatched position.

Fig. 2 is a view similar to Fig. 1 showing the bottom hole choke in anchored position.

Fig. 3 is a cross-sectional view taken on line 3—3 of Fig. 2.

Fig. 4 is an enlarged detail sectional view of a portion of Fig. 2 showing the details of the latching mechanism.

An embodiment of the present invention is shown in the drawing applied to the lower end of the well tubing 1. As illustrated, a special fitting or coupling 2 is secured to the lower end of the tubing 1. This fitting has a tapered bore therethrough decreasing in diameter downwardly from the lower end of the tubing and forming a restriction 3, which serves as a guide and anchor for the choke assembly. The restriction has a plurality of ducts 4 extending axially therethrough and spaced about the central bore for the flow of material through the fitting 2 when the choke assembly is in the bore thereof.

Spaced a substantial distance below the fitting 2 and connected thereto by means of a section of tubing 1b is a second special fitting 5 which is threaded externally at 6 to provide connection for the tail portion 1a of the tubing, and internally threaded at 7 to provide a connection for the short length of small tubing 8. This small tubing 8 has a choke seat 9 on its lower end providing an upwardly facing shoulder against which the choke apparatus is adapted to seat so as to limit its downward movement. The entrance from above into both of the fittings 2 and 5 is tapered so as to guide the choke assembly into place upon being lowered into the well tubing.

The choke assembly proper consists of a body portion made up of a plurality of elements. Among these elements is a tubular member or choke tube 10 having sealing cups 11 surrounding its exterior and adapted to provide a seal within the tubular extension 8. Tubular member 10 is threaded at its lower end to receive the choke or bean 12 which has a bore therethrough of a predetermined size to determine the rate of flow of fluid.

On its upper end the tubular member 10 is provided with a valve seat adapted to receive a ball valve 13 which will permit upward flow but prevent downward flow therethrough. Connected to this upper end and forming a cage or chamber for the ball valve 13 is a device 14 having lateral passageways or ports 15 therein so that after oil has passed through the bore of the tubular member 10 and emerged past the valve 13 it may flow through the ports 15 and enter the annular space within the well tubing about the choke assembly and thereafter flow upwardly through this annular space.

Secured to the upper end of the cage 14 is the solid body 16 of the holdown apparatus or latch assembly which has a slot 17 therethrough in which is disposed the latch dog or pawl 18. This dog is pivoted within the slot at its lower end at 19 and there is a spring 20 arranged to urge the dog radially outwardly at all times to a position to engage the shoulder on the lower end of the restriction 3 upon upward movement of the assembly.

Telescopingly engaged over the upper end portion of the body 16 is an actuating sleeve 21 having an opening 22 therein through which the pawl 18 may move into latching position as shown in Fig. 2 of the drawing. The upward and downward movement of the sleeve 21 is limited and the sleeve is prevented from turning on the body 16 by the pin 22 which extends through a pair of oppositely disposed slots 23 in the sleeve 21 and is fixedly carried in the upper end portion of the body 16. At its upper end the sleeve 21 is internally threaded to receive a fitting 24 having a pin 25 projecting upwardly therefrom and adapted to receive an ordinary fishing tool. The pin 25 may be provided with an opening 26 therethrough to permit of the attachment of a cable or wire line whereby the assembly may be lowered into and removed from a well.

It will be realized that when an upward pull is exerted on the pin 25 this will move the sleeve 21 upwardly with respect to the body 16 and will serve to retract the dog 18 as illustrated in Fig. 1. Fitting 24 may be omitted and the sleeve 21 may be secured directly to the lower end of a working barrel of a pump employed to pump fluid from a well.

Whenever it is desired to change the choke 12 either for the purpose of altering the internal diameter and hence the permissible flow from the well or for the purpose of replacing a worn element, all that is necessary is to lower the fishing tool over the pin 25 and pull upwardly. This will serve to unlatch the dog 18 as shown in Fig. 1 and thereupon the entire device may be quickly hoisted to the surface of the ground.

From the foregoing it will be appreciated that the choke assembly including the latch or hold-down assembly can be made of such overall external dimensions as to pass through the well tubing 1 regardless of the presence of any reasonable restrictions therein and yet be securely latched in position in the lower portion of the

tubing and released when removal is desired. Also the construction provides for the free flow of fluid up through the choke tube 10 through cage 14 into the space within the well tubing 1b about the choke assembly and up through the ducts 4 into the well tubing 1, when the choke assembly is in its operative position.

Having described the invention, we claim:

1. A bottom hole choke assembly for well tubing comprising a fitting interposed in the tubing and having a tapered bore therethrough the minimum diameter of which is at least as small as the minimum interior diameter of the tubing above said fitting, including restrictions due to devices incorporated therein, said fitting having by-pass ducts to afford a fluid flow path around the portion of said bore of minimum diameter, a releasable latch assembly including a body, a latch dog carried by the body for engagement with the fitting, and latch dog retracting means, said latch assembly having an overall exterior dimension small enough to enable movement thereof through said tapered bore, a choke carried by the lower portion of said latch assembly of a diameter small enough to pass through the tapered bore, and a seat carried by the tubing below said fitting for receiving the choke.

2. A bottom hole choke assembly for well tubing comprising a latch assembly including a releasable latch for latching the assembly in the lower portion of the well tubing, a choke tube, said latch assembly and tube having overall exterior dimensions smaller than the smallest interior cross section of the well tubing above the position at which the choke tube is to be located, a fitting connecting the upper end of the tube to the lower portion of the latch assembly, said connecting fitting having a chamber communicating with the interior of said choke tube, said chamber having port means placing the interior of the chamber in communication with the exterior thereof, and means for guiding and centering the choke tube within the well tubing when the choke tube approaches its operating position within the well tubing.

3. A bottom hole choke assembly for well tubing comprising a latch assembly including a releasable latch for latching the assembly in the lower portion of the well tubing, a choke tube, said latch assembly and tube having overall exterior dimensions smaller than the smallest interior cross section of the well tubing above the position at which the choke tube is to be located, a fitting connecting the upper end of the tube to the lower portion of the latch assembly, said connecting fitting having a chamber communicating with the interior of said choke tube, said chamber having port means placing the interior of the chamber in communication with the exterior thereof, and means in said well tubing for centering the latching assembly therein, said centering means having ducts extending therethrough for the flow of material discharged through said port means into the space between the latch assembly and the well tubing up into the well tubing above said centering means.

4. A bottom hole choke assembly for well tubing comprising a latch assembly including a releasable latch for latching the assembly in the lower portion of the well tubing, a choke tube, a fitting connecting the upper end of the tube to the lower portion of the latch assembly, said connecting fitting having a chamber communicating with the interior of said choke tube, said chamber having port means placing the interior of the cham-

ber in communication with the exterior thereof, and a check valve for preventing flow from said chamber into said choke tube.

5. A bottom hole choke assembly for well tubing comprising a latch assembly including a releasable latch for latching the assembly in the lower portion of the well tubing, a choke tube, said latch assembly and tube having overall exterior dimensions smaller than the smallest interior cross section of the well tubing above the position at which the choke tube is to be located, a fitting connecting the upper end of the tube to the lower portion of the latch assembly, said connecting fitting having a chamber communicating with the interior of said choke tube, said chamber having port means placing the interior of the chamber in communication with the exterior thereof, means in said well tubing for centering the latching assembly therein, said centering means having ducts extending therethrough for the flow of material discharged through said port means into the space between the latch assembly and the well tubing up into the well tubing above said centering means, and a check valve for preventing flow from said chamber into said choke tube.

6. A bottom hole choke assembly for well tubing comprising a fitting interposed in the tubing and having a tapered bore therethrough the minimum diameter of which is at least as small as the minimum interior diameter of the tubing above said fitting, including restrictions due to devices incorporated therein, said fitting having by-pass ducts to afford a fluid flow path around the portion of said bore of minimum diameter, a releasable latch assembly including a body, a latch dog carried by the body for engagement with the fitting, and latch dog retracting means, said latch

assembly having an overall exterior dimension small enough to enable movement thereof through said tapered bore, a choke, means connecting the choke to the lower portion of the latch assembly and placing the upper portion of the choke in communication with the space between the latch assembly and the surrounding well tubing, and a choke seat in said tubing below said fitting.

10 5. A bottom hole choke assembly for well tubing comprising a latch assembly including a releasable latch for latching the assembly in the lower portion of the well tubing, a choke tube, means for suspending the choke tube from the 15 lower end of the latch assembly with the upper end of the choke tube free to communicate with the space in the well tubing about the latch assembly, a choke on the lower end of the tube, and means for centering said latch assembly in said 20 tubing without completely closing the space between the latch assembly and the well tubing.
